UNITED STATES PATENT OFFICE.

PETER M. BROADFOOT, OF DECATUR, ALABAMA.

WHEELED SCRAPER.

SPECIFICATION forming part of Letters Patent No. 485,085, dated October 25, 1892.

Application filed June 22, 1892. Serial No. 437,585. (No model.)

To all whom it may concern:

Be it known that I, PETER M. BROADFOOT, a citizen of the United States, residing at Decatur, in the county of Morgan and State of Alabama, have invented a new and useful Wheeled Scraper, of which the following is a specification.

The invention relates to improvements in wheeled scrapers.

10 The object of the present invention is to provide a brace adapted to be applied to wheeled scrapers to strengthen the same at the connection between the tongue and the scraper-frame and to prevent sagging at the 15 rear of the tongue.

A further object of the invention is to provide means for holding the scoop in an elevated position for traveling.

10 The invention consists in the construction and novel combination and arrangement of parts, hereinafter more fully described, illustrated in the accompanying drawings, and pointed out in the claims hereto appended.

In the drawings, Figure 1 is a perspective 25 view of a scraper constructed in accordance with this invention, the scoop being shown elevated. Fig. 2 is a side elevation, the scoop being shown in operative position. Fig. 3 is a detail sectional view.

30 Like numerals of reference indicate corresponding parts in all the figures of the drawings.

1 designates a longitudinally-disposed brace having its front end 2 secured to a tongue 3 35 and its rear end 4 connected to the inner ends 5 of transversely-disposed braces 6, which have their outer ends secured to the sides 7 of a scraper-frame 8. The braces 1 and 6 are inclined and have their upper ends supported 40 by a vertical bolt 9, which passes through the tongue and horizontal plates 10 and is provided at its lower end with a head and has its upper end threaded and provided with a nut, which bears against the rear end 4 of the brace 45 1, which rear end is bent horizontally. The inner end of the transverse braces are bent vertically and have pivoted between them a rearwardly-extending bar 11. The plates 10 are arranged on the upper and lower faces of 50 the tongue and serve to strengthen the same and are secured in place by the vertical bolt or rod 9 and by a bolt 12, which secures the

front end of the brace 1 to the tongue. The inclined braces 1 and 6 support and strengthen the rear end of the tongue and scraper-frame 55 and prevent sagging or breaking when the scraper is loaded.

The pivoted bar 11 is provided with a hook 12^x and is curved at 13 in advance of the hook and is provided with an integral rearwardly depending handle 14. The hook 12^x is adapted to engage a shoulder 15 of the scoop to hold the latter elevated when the scraper is being moved from one place to another. The front end 16 of the pivoted bar 11 is provided with 65 a half-turn and enlarged and adapted to engage the vertical rod 9 to maintain the pivoted bar in an inclined position.

The transverse braces 6 are constructed of a single piece of metal, which is provided intermediate its ends with a vertically-disposed 70 rectangular bend to form the vertical ends 5 of the braces.

It will be seen that the manner of bracing the scraper is simple and comparatively inexpensive in construction and that the brace may be readily applied to any ordinary 75 wheeled scraper.

The hook of the pivoted bar is automatic in its operation, and as soon as the scraper is 80 dumped it engages the stop and holds the body of the scraper in a position for traveling without requiring the assistance or attention of the operator.

What I claim is—

1. The combination, with a wheeled scraper, of the inclined longitudinal and transverse braces having their upper ends connected together and their lower ends secured, respectively, to the tongue and to opposite sides of 90 the scraper-frame, and the supporting-rod extending vertically from the tongue and passing through the longitudinal brace, substantially as described.

2. The combination, with a wheeled scraper, 95 of the inclined transverse braces constructed of a single piece of metal, having its ends secured to the sides of the scraper-frame and provided intermediate its ends with a vertically-disposed bend, the longitudinal brace 100 having its ends bent horizontally, the front one being secured to the tongue and the rear one to the bend of the transverse braces, plates secured to the upper and lower faces of

85

100

the tongue, and a vertical rod passing through the tongue and through the longitudinal brace, substantially as described.

3. The combination, with a two-wheeled scraper, of inclined transverse braces constructed of a single piece of metal, having its ends secured to the sides of the scraper-frame and provided intermediate its ends with a vertical bend, a longitudinal brace extending upward from the tongue and having its rear end secured to the transverse braces at the bend, a vertical rod, and a bar pivoted at its front end in the bend of the transverse braces and provided at its rear end with a hook adapted to engage the scoop of the scraper to hold the same in an elevated position, substantially as and for the purpose described.

4. The combination, with a two-wheeled scraper, of inclined transverse braces constructed of a single piece of metal, having its

ends secured to the sides of the scraper-frame and provided intermediate its ends with a vertical bend, the inclined longitudinal brace having its rear end secured to the bend and its front end secured to the tongue, the vertical rod, and the bar having its front end pivoted in the bend and provided with a hook arranged at its rear end to engage the scoop and having a handle, said bar having its rear end engaging the rod, whereby the bar is held in an inclined position, substantially as described. 25 30

In testimony that I claim the foregoing as my own I have hereto affixed my signature in the presence of two witnesses.

PETER M. BROADFOOT.
